DIPLEX ANTENNA FEED SYSTEM

Michael E. Hiehle, Syracuse, N. Y., assignor to
General Electric Company, a corporation of
New York

Application July 30, 1948, Serial No. 41,628

7 Claims. (Cl. 178—44)

1

This invention relates to high frequency electrical transmission systems, and more particularly to systems for feeding energy from two transmitters, operating at different frequencies, to a common load. Such systems are used in television apparatus for simultaneously feeding energy from a visual transmitter and an aural transmitter to a single antenna and are often referred to as dippers.

The dippers embodying this invention operate on the principle of simultaneously feeding energy from two transmitters to a common load through an intermediate circuit. Briefly, energy from one transmitter is fed, in a push-pull relationship, to two utilization points, while that from the other transmitter is fed, in a parallel relationship, through the midpoint of a half wavelength loop connecting the utilization points. By proper selection of the characteristic impedances of the sections, both transmitters may feed into the same load and yet remain completely decoupled. These principles are well known in the art and will not be described in detail. My invention resides in certain improved constructional features of the diplexer assembly, and more particularly in the utilization of the outside sheaths of single coaxial transmission lines to perform functions separate from those of the inside conductors.

One of the objects of the present invention is to provide a new and improved diplexer to enable two transmitters, operating at different frequencies, to feed simultaneously to the same antenna, in such a manner that there is no reaction between the transmitters over a wide range of frequencies.

A further object of this invention is to provide a new and improved diplexer for guiding energy from a pair of transmitters to a pair of antennae through single concentric transmission lines in such a manner that there is no reaction between the transmitters, and the energy from both transmitters is radiated in phase quadrature at one antenna with respect to energy at the other antenna.

A further object of the present invention is to provide new and improved means for adjusting the electrical elements of a diplexer so as to make it operative over a wide range of frequencies.

For additional objects and advantages, and for a better understanding of the invention, attention is now directed to the following description and accompanying drawing, and also to the appended claims in which the features of the invention

believed to be novel are particularly pointed out.

In the drawing, Fig. 1 is a perspective view of a diplexer embodying my invention, with part of its container cut away to facilitate understanding of its internal arrangement, Fig. 2 similarly shows another diplexer embodying my invention in modified form, and Fig. 3 shows a modification of the diplexer of Fig. 1.

In both Fig. 1 and Fig. 2, the symbol

$$\frac{\lambda_v}{4}$$

refers to a quarter wavelength at the operating frequency of the visual transmitter, while the symbol

$$\frac{\lambda_o}{4}$$

refers to a quarter wavelength at the mean frequency of the design range of the diplexer.

Referring to Fig. 1, there is shown a concentric transmission line comprising an outer sheath 11, and an inner conductor 12 which is adapted to receive energy from a visual television transmitter at a visual input point 3. A similar concentric line 32 is shown divided into two parallel branches at a point 31 from whence two concentric lines 33 and 34 feed energy into the system. The transmission line 32 is adapted to be energized from an aural television transmitter at the aural input point 4. The parallel branches are terminated at the right end wall of a conductive container 10, and the branches 33 and 34 are of such length that together they form a loop one-half wavelength long at the mean operating frequency of the visual transmitter. While the container 10 has been shown as rectangular in form, it is to be understood that it can be of any convenient form, such as a tubular can for instance.

Two concentric transmission lines 24 and 26 with inner conductor 23 and 25 also terminate in the right end wall of the container. There are adapted to supply energy at output terminals 1 and 2 to a pair of antennae. For the purpose of obtaining a phase quadrature relationship in the output of one antenna with respect to the output of the other, a loop 27 is introduced in the concentric line 26. This loop is a quarter of a wavelength long at the mean operating frequency of the system, taking into account the frequencies of both the visual and aural transmitters.

The line sections 11 and 13 within container 10 are arranged to provide two intermediate points 7 and 8 from which energy from the visual trans-

mitter can be supplied in a push-pull relationship to the antenna terminals. To accomplish this, the outer sheath 11 of the visual input concentric line is terminated at point 7, at a distance of approximately one-quarter wavelength, at the operating frequency of the visual transmitter, from the left end wall of container 10. Point 8 is provided by the free end of a sheath 13 similar to sheath 11 and symmetrically disposed inside the container. Instead of terminating sheath 13 at the left end wall of the container, it is curved at this wall to join the outer sheath 11, and its left section is actually a concentric line containing an inner conductor 14 which is connected to the visual input line at a point 16. A shorting plug 15 provides a conductive connection between the inner conductor 14 and the sheath 13. The section of transmission line from point 16 to the shorting plug, considered solely as a concentric line and without reference to the function of the outer sheath in the container, provides a matching stub removed approximately one-quarter wavelength from the termination 7 of the visual input line. This matching stub is employed for the purpose of broadening the band pass of the system about the visual input frequency so as to permit operation over a two to one frequency range. The container 10, surrounding sheath 11, isolates it from ground at the operating frequency so that the voltage between the inner conductor 12 and sheath 11 is approximately balanced to ground at the intermediate point 7. The inner conductor 12 of the visual input line is connected by a short conductive link 21 to sheath 13 at point 8. The energy is thereby transferred into the field existing between sheaths 11 and 13. These sheaths 11 and 13 together constitute a two-wire transmission line. A shorting bar 22, for which a capacitance may be substituted in certain cases, is mounted so that it can be slid over the sheaths 11 and 13 so as to adjust their electrical length. The sliding bar is normally adjusted so that the quarter wave stub constituted by sheaths 11 and 13 constitutes a very high impedance at the visual input frequency, as seen from points 7 and 8. Two pairs of capacitor plates 35 and 36, mounted at the free ends of sheaths 11 and 13, provide additional lumped capacity to broaden the aural frequency bandwidth of the system and to insure electrical balance for the visual input.

Points 7 and 8 are connected by two short conductors 19 and 20 to the inner conductors of the half wavelength loop of the aural input line formed by concentric lines 33 and 34. Since the loop is a half wavelength long at the frequency of the visual transmitter, any voltage introduced at one terminal will produce an equal voltage of opposite phase at the other terminal. Accordingly, if the terminals are connected to two points carrying out-of-phase voltages, such as points 7 and 8, there will be no disturbance of the voltage relations at these points. Moreover, such voltages applied at the input terminals arrive at the junction point 31 in an out-of-phase relationship so that no visual current can flow past the junction point to the aural transmitter. The end result will be that the aural transmitter is coupled to supply parallel voltages to points 7 and 8 and yet remains completely decoupled from the visual transmitter.

The sheaths 11 and 13, while they have already been considered as a pair of linear conductors constituting a quarter wavelength stub inside container 10, can also be considered as

forming, in parallel, a single inner conductor inside container 10. When the sheaths 11 and 13 are excited in parallel, an electric field will exist between them and container 10. The length of the conducting path is close enough to a quarter wavelength at the operating frequency of the aural transmitter so as to offer a comparatively high impedance between points 7 and 8 in parallel, to the boundary of the container. Accordingly the voltage from the aural input line exists between points 7 and 8 in parallel and the container boundary. This voltage cannot affect the visual transmitter, because the same voltage exists on point 7 as on point 8 and hence there can be no difference of potential between point 7 and the inner conductor 12 of the visual input line at the aural frequency. The result of the arrangement is that the visual transmitter supplies voltages to points 7 and 8 in a push-pull relationship and yet remains completely decoupled from the aural transmitter.

A pair of short connectors 17 and 18 couple the voltages existing at points 7 and 8 to the inner conductors 23 and 25 of the antenna output lines. The antenna output lines are thus supplied with voltages in a push-pull relationship from the visual transmitter and in a parallel relationship from the aural transmitter. An external quarter wavelength loop in the concentric line 26 provides a phase retardation of 90° in that line so that the voltages arrive at the antennae in phase quadrature.

The arrangement of Fig. 1, as thus far described, has the advantage of utilizing single concentric lines to perform all the functions required in the diplexer. The lines inside the container perform multiple functions: as a concentric matching stub, considering the inner section of line 13 from point 16 to shorting plug 15; as a two-wire transmission line, considering sheaths 11 and 13 as a pair of linear conductors; and as a high impedance considering sheaths 11 and 13 as elements in parallel with respect to the container as an outer conductor. The sliding bar 22, enables the diplexer to be quickly adjusted to operate effectively at any frequency within a two-to-one range of frequencies, and thus only one adjustment is required to tune the system. This arrangement has been found very efficient in practice and economical with respect to manufacturing costs. In practice coaxial lines 24, 33, 34 and 26 are folded back to lie against the inside bottom of container 10.

Referring to Fig. 2, there is shown a concentric transmission line composed of an outer sheath 50 and an inner conductor 51 which is adapted to receive energy from a visual television transmitter at an input point 43. A similar concentric line 66 is shown divided into two parallel branches 68 and 69, at a point 67, from whence the two parallel branches feed energy into the system. The transmission line 66 is adapted to be energized from an aural television transmitter at input point 40. The parallel branches are terminated at the right end wall of a rectangular conductive container 45, and they are of such length, that together they form a loop one-half wavelength long at the mean operating frequency of the visual transmitter. Two concentric lines 46 and 48 enter the container through the left end wall and terminate at points 77 and 78 at a distance from the left end wall, of approximately one-quarter of a wavelength at the operating frequency of the visual transmitter. The inner conductors 47

and 49 continue directly to the right end wall of the container 45, and are there conductively connected to it. The sheaths 46 and 48 are, everywhere along their length, in contact, respectively, with the sheath 50 of the visual input line and a dummy sheath 52, symmetrically located with respect to sheath 50 inside the container. As in the diplexer of Fig. 1, the outer sheath 50 and dummy sheath 52 form elements of an open-wire transmission line section, shorted at its left end by means of adjustable shorting straps 57.

As in the case of the embodiment shown in Fig. 1, the pairs of sheaths are excited in push-pull from the visual input and in parallel from the aural input. This diplexer is intended to operate at a higher frequency than that of Fig. 1 and it has been found expedient to neutralize the inductance inherently present in the connecting link 56, by means of a series capacitance. This inductance is shown in dotted outline in Fig. 2. The neutralization is effected by running an inner conductor 53 into the dummy sheath 52. The short length of inner conductor 53 into sheath 52 can be considered as an open-ended transmission line and accordingly provides a capacitance whose value can be altered by adjusting the length of the inner conductor. In addition to the effective series reactance of link 56, stray capacity to container 45 from link 56, provides a shunting reactance across line 41, thus unbalancing the push-pull operation of the visual energy. To compensate for this effect a small coil 70 is connected between link 56 and the right end wall of the container and is chosen to provide parallel resonance in conjunction with the stray capacity.

Since the inner conductors of the antenna output lines are connected directly to the right wall of the grounded container, the voltages existing on the outer sheaths at points 77 and 78 are transferred to the inner conductor through the length of the quarter wave section going to the left wall of the tube. Thence the output voltages are transmitted to the antenna through regular single concentric lines. A quarter wave loop 65 is introduced in one of the lines to provide a quadrature relationship in the voltages at the antenna.

The construction shown in the embodiment of Fig. 2 also has the advantage of using ordinary concentric lines to perform all the necessary functions. The inversion of the feed to the antenna by the grounding of the inner conductors inside the tube has the advantage of more easily achieving the low impedance match required.

Fig. 3 shows a modification of the diplexer of Fig. 1 in which the inherent inductance of the connecting link 21 is neutralized in the same manner as in the diplexer of Fig. 2. This is particularly useful for operation at higher frequencies. Thus, in Fig. 3 the link 21' is not connected directly to the free end of sheath 13, but extends into its open end by a distance such that the capacity therebetween resonates with the inherent inductance 56' represented in dashed outline. Otherwise, the arrangement and operation of this modification are the same as for the diplexer of Fig. 1.

While certain specific embodiments have been shown and described, it will, of course, be understood that various modifications may be made without departing from the invention. The appended claims are therefore intended to cover any such modifications within the true spirit and scope of the invention.

What I claim as new and desire to secure by Letters Patent of the United States is:

1. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point, a linear conductor in said container substantially parallel to said portion, said linear conductor having one end connected to said wall adjacent said point of entrance and having a free end forming a second feed point adjacent said first feed point, said outer sheath and linear conductor together forming an open-wire transmission line section, means comprising an adjustable shorting member bridging said section for independently adjusting the effective length of said section at the operating frequency of said first transmitter, circuit connections for supplying wave energy from said inner conductor to said second feed point, said feed points being energized in opposite phase from said first transmitter, means for energizing said feed points in the same phase from said second transmitter, said means comprising a pair of unbalanced transmission line sections energized in parallel, said line sections each having a length substantially equal to an odd number of quarter-wavelengths at the operating frequency of said first transmitter, and a pair of transmission lines energized from said respective feed points for supplying energy from said points to said pair of load circuits.

2. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point, a conductive tube in said container, said tube having an unsupported section extending substantially parallel to said portion and a bent end section conductively connected to said sheath near said point of entrance so as to form a branch sheath, an inner wire within said tube joined at one end to the inner conductor of said line and at the other end to an adjustable short-circuiting member within said tube, whereby said tube encloses a concentric impedance-matching stub for said line, a low impedance connection between the free end of said straight section and said inner conductor, means for adjusting the length of the two-wire transmission line formed by said line portion and said straight section to provide a second feed point at the free end of said section energized in phase opposition to said first feed point, means for energizing said feed points in the same phase from said second transmitter, and a pair of transmission lines energized from

said respective feed points for supplying energy from said points to said pair of load circuits.

3. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point, a conductive tube positioned in said container substantially parallel to said portion, said tube being conductively supported only at one end at said wall adjacent said point of entrance and providing a second feed point at its free end adjacent said first feed point, a linear conductor positioned within the free end of said tube and having a direct connection to said inner conductor, said linear conductor penetrating said tube a sufficient distance to provide a capacity reactance substantially resonating with series inductive reactance inherent in said direct connection, said outer sheath and tube together forming an open wire transmission line section, means comprising a shorting member bridging said section for independently determining the effective length of said section at the operating frequency of said first transmitter, said feed points being energized in opposite phase from said first transmitter, means for energizing said feed points in the same phase from said second transmitter, and a pair of concentric cables energized from said respective feed points for supplying energy from said points to said pair of load circuits.

4. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point, a conductive tube positioned in said container substantially parallel to said portion, said tube being conductively supported only at one end at said wall adjacent said point of entrance and providing a second feed point at its free end adjacent said first feed point, a linear conductor positioned within the free end of said tube and having a direct connection to said inner conductor, said linear conductor penetrating said tube a sufficient distance to provide a capacity reactance substantially resonating with series inductive reactance inherent in said direct connection, said outer sheath and tube together forming an open wire transmission line section, means comprising a shorting member bridging said section for independently determining the effective length of said section at the operating frequency of said first transmitter, an inductance connected between said direct connection and the wall of said container, adjacent said feed points, to provide parallel resonance with

the stray capacitance of said direct connection, said feed points being energized in opposite phase from said first transmitter, means for energizing said feed points in the same phase from said second transmitter, and a pair of concentric cables energized from said respective feed points for supplying energy from said points to said pair of load circuits, each of said cables comprising an outer conductor and an inner wire, the outer conductor of one of said cables being in contact with said outer sheath along its length and the outer conductor of the other of said cables being in contact with said tube along its length, and said inner wires being conductively connected to a wall of said container adjacent said feed points.

5. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point, a conductive tube in said container, said tube having a straight unsupported section extending substantially parallel to said portion and a bent end section conductively connected to said sheath near said point of entrance so as to form a branch sheath, said outer sheath and said tube together forming an open wire transmission line section, means comprising a shorting member bridging said section for independently determining the effective length of said section at the operating frequency of said first transmitter, an inner wire within said tube joined at one end to the inner conductor of said line and at the other end to an adjustable short-circuiting member within said tube whereby said tube encloses a concentric impedance matching stub for said line, said tube providing a second feed point at its free end adjacent said first feed point, a linear conductor positioned within the free end of said tube and having a direct connection to said inner conductor, said linear conductor penetrating said tube a sufficient distance to provide a capacity reactance substantially resonating with series inductive reactance inherent in said direct connection, said feed points being energized in opposite phase from said first transmitter, means for energizing said feed points in the same phase from said second transmitter, and a pair of concentric cables energized from said respective feed points for supplying energy from said points to said pair of load circuits.

6. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within said container constituting a first feed point,

a linear conductor positioned in said container substantially parallel to said sheath, said conductor being electrically connected to said container near said point of entrance and having a free end forming a second feed point adjacent 5 said first feed point, means electrically connecting the inner end of said inner conductor to the free end of said linear conductor to maintain them at the same potential at said frequency, said outer sheath and linear conductor together forming an open-wire transmission line section, means comprising a shorting member bridging said section for independently determining the effective length of said section at the operating frequency of said first transmitter, 10 said feed points being energized in opposite phase from said first transmitter, means for energizing said feed points in the same phase from said second transmitter, said means comprising a pair of unbalanced transmission line sections energized in parallel, said line sections each having a length substantially equal to an odd number of quarter-wavelengths at the operating frequency of said first transmitter, and a pair of transmission lines energized from said respective 15 feed points for supplying energy from said points to said pair of load circuits.

7. A diplexer structure for supplying electrical wave energy to a common pair of load circuits from two separate high-frequency transmitters, comprising a closed conductive container, a concentric transmission line having an inner conductor and an outer sheath energized from a first one of said transmitters, said line having an end portion penetrating a wall of said container approximately an odd multiple of a quarter-wavelength at the operating frequency of said first transmitter, said outer sheath being connected to said wall of said container at its point of entrance and having a free end within 20 said container constituting a first feed point, a 25

linear conductor positioned in said container substantially parallel to said sheath, said linear conductor being electrically connected to said container near said point of entrance and having a free end forming a second feed point adjacent 5 said first feed point, means electrically connecting the inner end of said inner conductor to the free end of said linear conductor to maintain them at the same potential at said frequency, said outer sheath and linear conductor together forming an open-wire transmission line section, means comprising a shorting member bridging said section for independently determining the effective length of said section at the operating frequency of said first transmitter, said feed points being energized in opposite phase from said first transmitter, means for energizing said feed points in the same phase from said second transmitter, and a pair of transmission lines energized from said respective feed points for supplying energy from said points to said pair of load circuits.
